US00D647896S

(12) **United States Design Patent**
Chen et al.

(10) **Patent No.:** US D647,896 S
(45) **Date of Patent:** ** Nov. 1, 2011

(54) **COMPUTER ENCLOSURE**

(75) Inventors: **Yun-Lung Chen**, Taipei Hsien (TW);
Hong-Jin Wu, Shenzhen (CN); **Qun Wang**, Shenzhen (CN)

(73) Assignee: **Hon Hai Precision Industry Co., Ltd.**,
Tu-Cheng, New Taipei (TW)

(**) Term: **14 Years**

(21) Appl. No.: **29/381,765**

(22) Filed: **Dec. 22, 2010**

(51) **LOC (9) Cl.** 14-02

(52) **U.S. Cl.** D14/314

(58) **Field of Classification Search** D14/300-303,
D14/308, 314, 349, 351, 337, 355, 172, 218,
D14/240; D13/184, 199; D6/432, 436; D9/414,
D9/432; 312/223.1-223.2; 361/679.55,
361/679.6

See application file for complete search history.

(74) Attorney, Agent, or Firm — Altis Law Group, Inc.

(57) **CLAIM**

The ornamental design for a computer enclosure, as shown and described.

DESCRIPTION

FIG. 1 is a perspective view of the computer enclosure showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing of portions of the computer enclosure are for the purpose of illustrating environmental structure and form no part of the claimed design.
